UNITED STATES PATENT OFFICE

SYDNEY S. MCINTYRE, OF SEDRO-WOOLLEY, WASHINGTON

WINDING ENGINE FRAME

Application filed June 29, 1931. Serial No. 547,681.

My invention relates to improvements in winding-engine frames, and has for an object to provide a frame of sufficient rigidity for winding engines with the usual base frame 5 thereof omitted.

Hitherto, it has been customary, when making winding or hoisting engine frames, to use a rectangular rigid base frame on to which the side frames are fastened. My invention avoids this heavy and expensive base frame.

I attain this and other objects of my improvement with the construction illustrated in the accompanying sheet of drawing, forming a part of this specification, in which Figure 1 is a plan view of my winding-engine frame, Fig. 2 is an end elevation of Fig. 1, Fig. 3 is a front side elevation of the central gear-housing section and Fig. 4 is an end elevation of Fig. 3.

Similar characters refer to similar parts throughout. Certain parts are broken away to show other parts hidden thereby.

With more particular reference to designated parts: There are two side frames 5 and 6. Side frame 6 has axle pillow blocks a_6 and b_6 . Side frame 5 has similar pillow blocks not shown. In the pillow blocks a_6 is mounted the drum axle 12 rigidly clamped 30 therein by stud bolts engaged in the pillow blocks extending through axle caps 7 and 11 which are mounted on said axle. In the pillow blocks b_6 is mounted the drum axle 13 rigidly clamped therein by stud bolts engaged 35 in the pillow blocks and extending through caps 8 and 10 mounted on said axle.

On the foot flange of each side frame are two bosses 14, 14 each having an opening 15 therein for extending bolts therethrough for 40 fastening the frame to a sled, when used for logging, or to a stationary foundation when used for hoisting.

On the interior wall of each side frame is an annular, shift-gear housing projected toward each other with coinciding axes. On the side frame 5 is the housing 17 having an interior end flange a_{17} and gear chamber c_{17} . On the side frame 6 is the housing 18 having an interior end flange a_{18} and gear chamber 50 c_{18} . Within flange a_{18} is a central opening

b_{18} , and within flange a_{17} is a similar opening not shown. In the top wall of housing 17 is an opening 19 through which a gear mounted on axle 13 may protrude to engage a shift gear mounted in said housing. In 55 the top wall of housing 18 is an opening 20 through which another gear mounted on said axle 13 may protrude to be engaged by a shift gear in said housing. Central, hollow-cylindrical gear housing 21 has end 60 flanges a_{21} , a_{21} being disposed to bear on end flanges a_{17} and a_{18} , and holes 16 in flanges a_{21} register with holes in flanges a_{17} and a_{18} through which bolts 23 are extended and used to firmly clamp the intervening housing 65 21 to housings 17 and 18 and thus add another bond between side frames 5 and 6 to those provided by axles 12 and 13 which are clamped thereon. Thus firmly tied together, side frames 5 and 6 have no need for further 70 stability such as would be added by the usual base frame above referred to.

Centrally disposed in the front wall of housing 21 is neck 24 having an external flange 25 and provided with an opening 26 75 through said wall into central gear chamber 22.

As illustrated, gear housings 17 and 18 are integral with side frames 5 and 6, respectively. This has been the preferred construction in practice. With central gear housing 21 bolted to and between said side-frame housings, as illustrated, a stability of frame structure is attained quite sufficient to resist all operative strains without the added 80 strength of frame provided by the drum axles 12 and 13 clamped thereto. However, with the strength of structure secured through the union of said side frames, axles and housing assembly, as shown, an exceptionally strong frame is provided at a 85 relatively reduced cost because the expensive base frame, referred to, is not required.

In practice this frame construction is used in gasoline winding or donkey engines where 95 the prime mover speed needs considerable reduction. A shaft bearing is clamped to flange 25 and the outer end of an extension of the gas-engine shaft is mounted therein for revolution, and a smaller bevel gear is 100

fastened thereon within housing chamber 22. Bearings are clamped to flanges $\alpha 17$ and $\alpha 18$ and a counter-shaft mounted for revolution therein at right angles to said engine shaft and parallel with axles 12 and 13. A larger bevel gear is fastened on said countershaft engaged with said smaller bevel on the engine shaft. The ends of the countershaft in chambers $\alpha 17$ and $\alpha 18$ have splines therein and on them are mounted shift gears for oscillation and revolution therewith. A drum and gear are mounted on axle 13 for revolution, said gear being extended through opening 20 in housing 18 and engageable by said shift gear in the housing 18. A drum and gear are mounted for revolution on axle 12, said gear being extended through opening 19 in housing 17 and is engageable by said shift gear therein, said construction providing for the driving of said drums separately or simultaneously at different speeds.

These gears and drums do not form a part of the frame, which alone is the subject of this application, and their inclusion in the drawing would needlessly complicate the same. However, they are referred to in order that the purposes of this particular reduction to practice of the invention may be more easily understood.

Having thus disclosed my invention, what I claim as new therein and desire to secure by Letters Patent is,—

A winding engine frame including two side frames, two oppositely-disposed side-frame gear housings one being fastened to the inner wall of each of said side frames, an intervening gear housing being fastened to each of said side-frame gear housings joining the side frames, and a plurality of drum axles each being clamped to both of said side frames joining the same.

SYDNEY S. McINTYRE.
